(57) **CLAIM**

The ornamental design for a saddlebag tether as shown and described.

DESCRIPTION

FIG. 1 shows a perspective view of an exemplary embodiment of saddlebag tether;

FIG. 2 shows a front view of the saddlebag tether of FIG. 1; FIG. 3 shows a back view of the saddlebag tether of FIG. 1; FIG. 4 shows a left view of the saddlebag tether of FIG. 1; FIG. 5 shows a right view of the saddlebag tether of FIG. 1; FIG. 6 shows a top view of the saddlebag tether of FIG. 1; FIG. 7 shows a bottom view of the saddlebag tether of FIG. 1; and,

FIG. 8 shows a perspective view illustrating a pouch of the saddlebag tether of FIG. 1.

The dash-dash broken lines shown in the drawings illustrate stitching, and are included in the claimed design. The dash-dot-dash broken lines shown in FIG. 8 depict boundary lines of the claimed design and for no part thereof.

1 Claim, 8 Drawing Sheets
